UNITED STATES PATENT OFFICE.

PATRICK B. DELANY, OF NEW YORK, N. Y., ASSIGNOR TO THE STANDARD ELECTRIC MANUFACTURING COMPANY, OF SAME PLACE.

ELECTRICAL SYNCHRONOUS MOVEMENT.

SPECIFICATION forming part of Letters Patent No. 286,273, dated October 9, 1883.

Application filed April 12, 1883. (No model.)

To all whom it may concern:

Be it known that I, PATRICK B. DELANY, of the city, county, and State of New York, have invented certain new and useful Improvements in Electrical Synchronous Movements, 5 of which the following is a specification.

In several applications for Letters Patent of the United States, filed simultaneously herewith, I have shown several arrangements of 10 apparatus for obtaining the synchronous movement of instruments situated at different places and connected by an electric circuit. While in these applications several means of obtaining and maintaining a synchronous movement 15 are illustrated, the applications are alike in that they all show a circular table of insulated contacts, some of which contacts are connected up in different electric circuits and used either for telegraphic or other purposes, 20 and the remainder of the contacts devoted to maintaining the synchronous movement of the apparatus. The applications referred to were all filed of even date herewith, and are serially numbered 91,489, 91,490, 91,491, 91,492, and 25 91,493. In working such apparatus upon long lines the static induction created in the line is apt to interfere not only with the transmission of telegraphic messages or of electrical impulses for any purpose, but also interferes with 30 the correcting or regulating impulses which are transmitted over the line when the apparatus at either station tends to run out of time with that at the other station.

The object of my present invention is to provide 35 a means whereby the injurious static inductive effects may be absolutely and entirely obliterated on lines of any length, so that the apparatus works with as absolute accuracy as if such induced currents did not exist.

Figure 1 of the accompanying drawings illustrates 40 two stations, X and Y, connected by a main line; and Fig. 2 is a detail view of a modification.

At each station a circular table of insulated 45 contacts, T, is shown, and a trailing-finger, f, which is carried by a vertical shaft, to which the armature-disk F is fast, the disk being rotated by a motor-magnet, G G, placed in a motor-circuit, which is made and broken by

the vibrations of a tine of a fork, H, which is 50 automatically vibrated by a magnet, I I, included in a local-battery circuit. The motor-circuit is indicated by the broken line, and the local vibrating circuit by the dotted lines. The poles of the magnet I I are provided with 55 screw-extension pole-pieces i, which may be adjusted to or from the tines of the fork to regulate its speed of vibration. A shunt-resistance, R, is placed in the motor-circuit to prevent sparks between the contacts a b, and 60 a similar resistance, R', is placed in the local vibrating circuit, to prevent sparks between the contacts a' b'. Sixty contacts at each station are shown, and are numbered in six independent series from 1 to 10. Two contacts in 65 each series are shown as connected up in an independent circuit, of which there are four, as clearly illustrated, thus leaving the 9's and 10's in each circuit for maintaining synchronism. The apparatus at each of the stations 70 is illustrated diagrammatically. The table of contacts T is stationary, and the armature-disk F, which is rotated by the motor-magnets, is fast on the vertical rotary shaft F', which is connected with the line and carries a radial 75 arm, f', and a trailing-finger, f, which completes the electric circuit from the contact at one station over the line to the corresponding contact at the other station. This description is sufficient to enable any one skilled in the 80 art to construct an apparatus fulfilling the necessary conditions. The apparatus is, however, illustrated and described in detail in an application for improvements in telegraphy filed simultaneously herewith, and numbered 91,493, 85 and patented of even date with this, which application shows an apparatus identical with that herein illustrated, with the exception of the devices for preventing static disturbance, and any very detailed description of the operation is therefore superfluous here.

As the corresponding apparatus at each station, whatever it may be, is connected with the corresponding contacts, the circuit will be completed between those instruments whenever the synchronously-moving fingers at the two stations rest upon the contacts with which they are connected. If the vibrator is vibrated at

the rate of eighty-five per second, and there are thirty teeth in the armature-disk, the trailing finger will be rotated nearly three times per second; and, as under the organization shown, the corresponding instruments at each station are connected to two of the contacts in each of the six series, they will be placed in communication twelve times for every rotation of the trailing fingers, or thirty-four times per second. The circuit is therefore practically unbroken. The synchronous movement of the apparatus is maintained as follows: At station X, three of the 9's farthest removed from each other are connected together and to battery K, and that three of the 10's farthest removed from each other are connected to each other and to a line, 1, which passes through two correcting or regulating coils, I I', on the cores of the vibrator-magnet I I', and thence to ground. The remaining three intermediate 9's and 10's are thrown out or unconnected with any circuit. At station Y the 9's corresponding to those connected to the battery at station X are thrown out, while the alternate 9's which correspond with those thrown out at station X are connected with the battery K', and the 10's at station Y, which are connected with each other and with the correcting-coils I' I' on the cores of the vibrator-magnet, correspond with those which were thrown out at station X, the 10's at station Y corresponding to the connected 10's at station X being also thrown out or unconnected. At both stations the three 10's which are connected with the correcting coils on the cores of the vibrator-magnet are built out or extended toward the adjoining 9's, which are not connected with any circuit. When the trailing contact-arms f at both stations are moving synchronously and rest on corresponding contacts, and on about the same portions of those contacts, the four independent circuits will successively be completed, as described. If the apparatus at Y runs a trifle faster than that at X, the finger f at Y will touch the extended side of a 10 contact, while the finger at X is still on a battery-connected 9, a current or impulse of electricity will be sent from the battery K through the contact 9, and finger f at station X, over the line and through the contact 10 and line 1, to the coils mounted on the cores of the vibrator-magnet I. The effect of this pulsation of electricity is to increase the power of the vibrator-magnet and momentarily slow the vibration of the fork and the rotation of the armature disk and finger, and the trailing contact-finger f will immediately drop back into its proper relative position. The poles of the vibrator-magnet are placed on the outside of the tines, so that the tines vibrate in magnetic fields, which modify or in a measure overcome the normal speed of vibration. As this magnetic field is decreased in strength, the tines vibrate more freely, and consequently more rapidly. When, however, these exterior magnetic fields are increased or

supplemented by the action of the deterring-magnet L L, the resistance to the vibration of the fork is increased, and there is a consequent diminution in the rate of vibration. Exactly the same operation occurs if the contact-finger f at station X moves faster than that at station Y. There is, therefore, an automatic mutually-compensating correction from either end of the line, as the apparatus at one station moves faster than that at the other. As the connected 10's are extended toward the adjoining 9's, a variation of speed very much less than that sufficient to carry one trailing finger across the space between any two of the other contacts is immediately corrected, and there is no danger, therefore, of any disturbance by bridging before the variation is corrected. At station Y one of the thrown-out 9-contacts is connected to ground through a ticker or sounder, T, and when the apparatus is running synchronously there will be a stroke on the ticker at each revolution of the trailing finger. When the operator, therefore, hears a continued sound on the ticker, he knows that the instruments are running synchronously. In starting the apparatus the vibrator at station X is put in motion, as hereinbefore described, and the adjustment of the apparatus is completed by the operator at station Y. The fork at Y is started into vibration, and the switch M, between the connected 9's and the battery K', and the switch N, between the connected 10's and the correcting-coils, are left open. If the trailing fingers happen to start in synchronism, the sounder T will tick, and if the ticking continues for a short time the operator will know the apparatus is synchronous and closes the switches M and N, and the apparatus is in working condition. If the apparatus does not start in synchronism, there will be no sound at first on the ticker T, but the operator at station Y, by screwing the pole-pieces away from the tines of the fork, will cause them to vibrate at a speed which, by previous understanding, he will know to be very much greater than that of the fork at the distant station. The finger at Y will therefore gain rapidly on the finger at X, and as they occasionally come into conjunction there will be a stroke on the sounder. Then, by gradually adjusting the pole-pieces to approach them to the tines of the fork, the strokes on the sounder will become less frequent, and by continuing the adjustment the fingers will travel together sufficiently long to give a series of ticks on the sounder, and when the ticking on the sounder continues for several seconds or more the switches M and N are closed, and the apparatus is in proper condition, any subsequent variation being automatically corrected, as above described. As the circuit is made and broken many times in each revolution of the trailing fingers, and as the duration of contact between the fingers and the insulated contacts is very brief, the static

discharges from the line at each completion of the circuit are so disturbing, as on long lines, to destroy the synchronous movement of the apparatus. In order to overcome this difficulty and to absolutely guard the successive momentary completions of the circuits from the injurious and disturbing effects of the static discharge, I place between each of the contacts a thin insulated contact, indicated by *z* in the drawings. These extra static contacts are connected together at each station and put to ground. When, therefore, the trailing fingers in rotating pass from one contact, and a static current is created in the line, the finger *z* strikes the static contact *z* and the static discharge is put to the ground. The line therefore is completely discharged before the circuit is completed through the next insulated contact, and as the trailing fingers rotate the line is discharged before reaching the successive contacts. By this arrangement all disturbing effects from static induction are absolutely prevented, and the system works as perfectly as if such currents did not exist.

I have fully described the operation of the system shown in the drawings; but my invention is not dependent upon that special organization, but is clearly applicable to the various synchronous movements illustrated in the applications filed simultaneously herewith.

Instead of arranging the static discharge-contacts upon the stationary table, they may be carried on a separate disk in proper relation to the contacts, and the ground-connection be completed by a contact-finger, as illustrated in Fig. 2.

I have described the discharge or ground contacts as being for the purpose of discharging the line of static or inductive currents; but, of course, any charge on the line will be put to ground as the apparatus rotates.

Any subjects-matter herein shown or described, but claimed in cases 91,489, 91,490, 91,491, 91,492, or 91,493, filed of even date herewith, or No. 102,928, filed August 6, 1883, are disclaimed herein.

What I claim as my invention is—

1. The combination, substantially as set forth, of two electrically-connected stations, 50 a vibrator at each station, motor circuits and magnets, and rotary circuit-completers driven thereby, circular tables of contacts, some of the contacts thereon being apportioned into circuits for the transmission of electrical impulses for any purpose, other contacts thereon arranged in connection with suitable batteries for sending electrical impulses to maintain the synchronous movement of the apparatus at the two stations, regulating-magnets through 55 which electrical impulses are sent to correct the speed of the vibrators, and static dis-

charge-contacts placed between each of the contacts on the tables of contacts and connected to the ground.

2. The combination of a main line, a series 65 of like contacts electrically connected in independent groups, so that each contact is connected in a different group from the adjoining contacts, means for successively completing the line-circuit through said contacts, and a series 70 of line-discharge contacts electrically connected with the ground, placed between the first-named contacts, so that the line is discharged to earth before the completion of the circuit through each of the first-mentioned contacts. 75

3. The combination, substantially as set forth, of a main line, a series of like contacts arranged in a circle and electrically connected in independent groups, so that the circuit of each group is connected with a number of the 80 contacts placed at intervals around the circle, a circuit-completer which traverses the circle and successively and rapidly makes and breaks the line-circuit through each of the contacts, whereby the circuit of each group of contacts 85 is placed in connection with the main line a number of times in each traverse of the circuit-completer, and a series of line-discharge contacts connected with the ground placed alternately between the first-mentioned contacts, 90 so as to alternately make the main-line circuit through each of the first-named contacts and discharge the line to ground through each of the discharge-contacts.

4. The combination, substantially as set 95 forth, at electrically-connected stations, of a series of contacts at each station, some of which are connected for use, as described, and others of which are devoted to maintaining the synchronous movement of the apparatus, 100 mechanism at each station for successively making and breaking the line-connection with said contacts, electrically-controlled apparatus for continuously actuating such mechanism, means for automatically correcting the speed 105 of said circuit-breaking mechanisms reciprocally from one station to the other whenever they run out of time by impulses of electricity received from the distant station through the correcting-contacts, and a series of line-discharge contacts connected with the ground through which the line is discharged before its connection with each of said first-named contacts.

In testimony whereof I have hereunto subscribed my name this 3d day of April, A. D. 115 1883.

PATRICK B. DELANY.
